UNITED STATES PATENT OFFICE.

WILLIAM HENRY SMITH, OF PAWTUCKET, RHODE ISLAND.

BRAKE MECHANISM.

SPECIFICATION forming part of Letters Patent No. 716,775, dated December 23, 1902.

Application filed March 15, 1902. Serial No. 98,311. (No model.)

To all whom it may concern:

Be it known that I, WILLIAM HENRY SMITH, a subject of the King of Great Britain, and a resident of Pawtucket, in the county of Providence and State of Rhode Island, have invented a new and Improved Brake Mechanism, of which the following is a full, clear, and exact description.

The object of the invention is to provide a new and improved brake mechanism, designed for use on vehicles, hoisting, and other machinery, which is simple and durable in construction, very effective in operation, easily manipulated, and arranged to permit of setting the device to any desired degree of resistance, according to the use made of the vehicle or machine on which the brake mechanism is applied.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a sectional side elevation of a street-car on which the improvement is applied. Fig. 2 is an inverted enlarged plan view of part of the same. Fig. 3 is a transverse section of the same. Fig. 4 is a cross-section of the spring-mounted pulley for the brake-chain. Fig. 5 is an enlarged sectional side elevation of the car-axle, brake-disks, brake-wheel, and brake-band, parts being broken out; and Fig. 6 is a transverse section of the same.

The brake mechanism, as illustrated in the drawings, is supplied to car-axles A, carrying the wheels B and supporting the car-body C in the usual manner. On each axle A of the car are secured the disks D, preferably two in number, and from the faces of each of the disks extend transversely the bolts E, (see Fig. 6,) engaged under their heads by a spring F, pressing against the face of a disk G, held to slide transversely on the bolts E and compressed by the spring F against the web H' of the ring-shaped brake-wheel H, extending with its curved rim H² over the peripheral faces of the disks D and G, as plainly

indicated in Fig. 6. The rim H² is completely encircled by a brake-band I, having its ends I' crossing each other and extending in opposite directions, as plainly shown in Fig. 5, and the said ends I' are connected with the outer ends of levers J, fulcrumed on the under side of the car-body C.

By reference to Fig. 2 it will be seen that for the two brake mechanisms on each car-axle I provide two pairs of levers J, and the inner ends of each pair are connected with each other by plates K, pivotally connected by links L with the casing N, supporting a pulley N' and pressed on by a spring O, held on the under side of the car-body C. (See Fig. 4.) Over the pulley N' passes a brake-chain P, also passing over guide-pulleys Q, journaled on the car-body, to then extend in opposite directions to the ends of the car to connect with the drums R of brake-staffs R' under the control of the attendant of the car.

The spring O normally holds the casing N and the parts connected therewith in such a position that the brake-band I is drawn tight on the brake-wheel H for applying the brakes and bringing the car to a standstill; but when it is desired to release the brakes it is necessary for the attendant to work the brake-staff R', so as to exert a pull on the brake-chain P to draw the casing N transversely against the tension of the spring O. It is understood that when this takes place the movement of the casing N causes the links L to impart an outward movement to the plates K, so as to give a swinging motion to the inner ends of the levers J to move the outer ends of the said levers toward each other, and thereby release the brake-band I on the peripheral face of the brake-wheel H. By adjusting the bolts E the spring F is pressed with more or less force against the disk G, so that the latter clamps with more or less force the web H' between the disks D and G, and consequently the resistance desired to be given by the brake mechanism can be readily regulated by adjusting the bolts E previous to the car starting on its travel. It is understood that when the brake-band I releases the brake-wheel H then the latter rotates with the disks D and G as the car moves on its travel; but as soon as the operator releases the brake-staff R' then the

spring O and parts connected therewith cause the brake-band I to be drawn tight on the brake-wheel H, and consequently the wheel H is held against rotation, and thus offers resistance to the revolving disks D and G to finally bring the car to a standstill.

It is understood that both disks D and G are in frictional contact with the web H, so that when the latter is held against rotation by the brake-band I sufficient resistance is given to the said disks, and consequently to the axle A and wheels B, to bring the car to a standstill.

The levers J extend loosely through bearings J', which also form a stop for the levers to limit the swinging movement thereof after the spring O has acted on the several parts to apply the brakes, as above described.

By the use of my device abrupt or sudden stops of the car are entirely prevented, as the brake is gradually applied to bring the car to a standstill within a certain distance, which can be predetermined by adjusting the bolts E accordingly to increase or diminish the tension of the spring F and the friction between the disks D G and the brake-wheel H. Thus the device can be adjusted to bring the car to a stop within one, two, or more lengths of the car, according to the grades of the road over which the car is to travel.

It is understood that the arrangement may be reversed in such a manner that the brake is applied by the operator working the staff R', and the brake is released by the power of the spring O when the staff R' is released.

Having thus described my invention, I claim as new and desire to secure by Letters Patent—

1. A brake mechanism having revoluble friction-disks, a brake-wheel between the disks, and a brake-band engaging the brake-wheel, to brake the latter, as set forth.

2. A brake mechanism having revoluble friction-disks, of which one rotates with the other, a spring mounted to move one disk toward the other, a brake-wheel between the disks, and a brake-band engaging the brake-wheel, as set forth.

3. A brake mechanism having revoluble friction-disks, of which one rotates with the other, a spring mounted to move one disk toward the other, a brake-wheel between the disks, a brake-band engaging the brake-wheel, and means for regulating the tension of the spring, as set forth.

4. A brake mechanism having revoluble friction-disks, one of which is secured to a rotating part of the machine on which the brake mechanism is applied, the other brake-disk being mounted to slide toward and from the first-named disk, a spring compressing the sliding disk toward the other disk, and a brake-wheel made ring-shaped and clamped between the said disks by the spring-pressed disk, as set forth. 60

5. A brake mechanism having revoluble friction-disks, one of which is secured to a rotating part of the machine on which the brake mechanism is applied, the other brake-disk being mounted to slide toward and from the first-named disk, a spring compressing the sliding disk toward the other disk, a brake-wheel made ring-shaped and clamped between the said disks by the spring-pressed disk, and means for regulating the tension of the said spring, as set forth. 70

6. A brake mechanism having revoluble friction-disks, a brake-wheel between the disks, a brake-band completely encircling the brake-wheel and having its ends crossing each other and extending in opposite directions, and means for simultaneously drawing on the brake-band ends in opposite directions, to apply the brake-band on the brake-wheel, as set forth. 80

7. A brake mechanism having a brake-wheel, a brake-band completely encircling the brake-wheel and having its ends extending in opposite directions, and spring-pressed means connected with the ends of the brake-band to draw the latter outwardly in opposite directions, to apply the brake-band on the brake-wheel, as set forth. 90

8. A brake mechanism having a brake-wheel, a brake-band completely encircling the brake-wheel and having its ends cross each other and extending in opposite directions, levers pivotally connected with the outer ends of the said brake-band, a pulley journaled on a casing, a brake-chain engaging the said pulley, a spring pressing the said pulley-casing, and a connection between the said pulley-casing and the said levers, as set forth. 95 100

In testimony whereof I have signed my name to this specification in the presence of two subscribing witnesses.

WILLIAM HENRY SMITH.
